AUTOMATIC CATCHER FOR TIN PLATE

Dario Buccicone and Rudolph A. Fenoglio,
Gary, Ind.

Application May 18, 1938, Serial No. 208,692

5 Claims. (Cl. 271—68)

This invention relates to means for handling sheet or plate-like material, sometimes referred to as catching and piling mechanism. While not limited thereto, the particular embodiment of the invention illustrated is well suited for receiving tin plate from a shearing device and piling it at a station from which it will be subsequently removed for bundling and shipment.

The invention further relates to certain specific features of construction and combinations of interrelated instrumentalities, so arranged that traveling plate-like material is transversely bowed between its side edges to prevent the wobbling of long, flexible, normally unstable, sheets while they are being piled. Other features relate to such instrumentalities in cooperative association with mechanism effective to minimize the vertical distance through which the plates or sheets are dropped just prior to piling. For a more complete disclosure of the invention, reference is to be had to the following description, the accompanying drawings and the appended claims.

In the drawings:

Figure 1 is a diagrammatic view illustrating certain conveying and bowing mechanism embodying the invention;

Figure 2 is a diagrammatic transverse section on line II—II of Figure 1 showing the condition of a plate or sheet at about the time the bowing operation starts;

Figure 3 is a section on line III—III of Figure 1 showing a sheet bowed transversely by the mechanism;

Figure 4 is a plan of the complete machine, embodying various features of the invention;

Figure 5 is a side elevation thereof; and

Figure 6 is an end elevation as viewed from the left of Figure 5.

Referring in detail to the drawings, the numeral 10 represents generally a mobile base carried on suitable supporting wheels 11 of any conventional form. This base carries a plurality of uprights 12 forming vertical guides for a plurality of rods 13 which jointly support a frame-work 14 adapted to be raised automatically as the sheets piled by the mechanism accumulate.

The frame-work 14 carries suitable bearings for supporting parallel shafts 15 and 16, the former being located at what will be termed hereinafter in the receiving end of the machine, and the latter being located adjacent the delivery end thereof. The shaft 15 at the receiving end carries a plurality of transversely spaced, grooved pulleys 17 and 17^a of substantially uniform diameters. The shaft 16, at the delivery end, carries a pair of

outer grooved pulleys 18 of relatively large diameter and an intermediate pulley 19 of relatively smaller diameter.

Trained around the pulleys 17 and 18 there are parallel belts 20 which are adapted to support the sheets or plates P adjacent their side edges. Trained around the intermediate pulleys 17^a and 19 there is an intermediate belt 21. The pulley 19 is mounted with freedom to turn on the shaft 16 between collars, as shown, so as to compensate for the differential diameters of pulleys on the same shaft and thus prevent undue slippage between the belts and pulleys.

A shaft 22, mounted in adjustable bearings supported by the upper frame-work, carries a centrally located pulley 23. Arms 24, swingable about the axis of the shaft 22, support a pulley 25. A pressure belt 26 is trained around the pulleys 23 and 25, and, in coaction with the other belts 20 and 21, serves to gradually or progressively bow the sheet transversely while feeding it from the receiving end of the mechanism toward the delivery end thereof. Such progressive bowing of the sheet transversely will be apparent by comparison of Figures 2 and 3. The sheet is in a substantially flat or straight condition when it is received by the conveyer, and at the instant it is subjected to the coaction of the lower belts 20—20 and 21 and the upper pressure belt 26, it is flexed downwardly along its longitudinal medial line; this downward or flexing action increases progressively as the sheet approaches the region between the shafts 16 and 22. Thus the sheet is transversely dished as it is fed out, and overhangs the discharge end of the conveyer. This serves to stiffen the unsupported end thereof and facilitates the proper feeding and piling of long sheets of relatively thin, flexible metal or like material.

The sheets discharged by the belts are accumulated at a receiving station which may take the form of a platform or table 27. End stops 28 are provided which arrest the forward travel of each sheet, and side guides 29—29 serve to confine, pile and guide the side edges of the sheets as they fall into position on the pile. The end stops 28 and side guides 29 are supported by respective carriages 29^a slidably mounted on a cross member 29^b, the stops 28 being secured to rods 31 telescoping into bearings 32 carried by extensions 33 forming parts of the respective carriages.

The belts 20—20 and 21 are maintained in a relatively taut condition by means of a slack take-up device including pulleys 34 carried by a cross-shaft 35 mounted in pivotably supported arms 36

which are urged downwardly by a suitable weight 37.

In order to minimize the vertical fall or drop of the plates or sheets as they are discharged from the feeding belts to the receiving station, means are provided which are synchronized with the feeding of the sheets so as to automatically and gradually elevate the conveyer mechanism. These means include a crank-pin 38 which is eccentrically adjustable in a disk 39 carried on a shaft 40 which carries a gear 41 arranged to be driven by a pinion 42 secured to the pulley-carrying shaft 15.

A pitman 43 transmits the movement of the crank-pin 38 to a rocker arm 44 carrying a pawl 45 which coacts with a ratchet-wheel 46 secured to a shaft 47 carrying a worm 48 which meshes with a worm-gear 49 secured to a shaft 50 which carries a pinion 51 meshing with rack-teeth 52 formed on certain of the rods 13. This worm-driven rack and pinion is arranged in duplicate at opposite sides of the machine, as will be apparent from Figures 4 and 6.

The metal plates or sheets handled by the feeding and stacking device are adapted to be received, for example, from any suitable conveyer mechanism, such as a conveyer being diagrammatically indicated at 53, which may be assumed to be a belt or chain conveyer carrying the plates either directly from the tin pot or from a shear. The mechanism described may be driven from any suitable prime mover. In the embodiment illustrated, the main drive is transmitted through a gear 54 which is adapted to be driven from a conventional form of strip or plate shear, not shown.

From the detailed description and examination of the drawings it is apparent that the mechanism described is of simple design, yet quite effective to continuously feed successive sheets from the receiving toward the delivery end of the catcher and to gradually bow them transversely prior to stacking. As the pile of plates or sheets accumulates, the feeding mechanism will be bodily adjusted vertically so as to minimize the vertical distance through which the same will fall. Upon accumulation of a stack of sheets of the desired height, the end stops and side guides can be readily moved out of the way so as to give access to the pile, which can be removed as a unit by any suitable means, such as overhead tackle or hand truck.

While we have described quite precisely certain specific features of the embodiment of the invention illustrated, it is to be understood that various modifications and substitutions of equivalents may be made by those skilled in the art without departure from the invention, as defined in the appended claims.

60 We claim:

1. An automatic catcher and piling mechanism comprising a plurality of belt-like members trained around spaced pulleys, at least one of which is of a diameter smaller than the others, an intermediate belt-like member trained over spaced pulleys, one of which is juxtaposed to the aforesaid smaller pulley so that as a sheet supported near its side edges by a pair of said mem-

bers is fed forwardly it will be bowed transverse by the intermediate belt-like member.

2. An automatic catcher and piling mechanism comprising a substantially parallel pair of endless belts trained around respective pulleys, an intermediate belt trained around intermediate pulleys, one of the intermediate pulleys being of smaller diameter than the pulleys for the first mentioned belts, and a traveling member effective to gradually bow transversely a sheet supported jointly by said belts. 5

3. An automatic catcher and piling mechanism comprising a vertically adjustable frame-work, a shaft at the receiving end thereof carrying a plurality of pulleys of substantially equal diameters, a second shaft at the delivery end of the frame-work carrying outer pulleys of relatively large diameters and an inner pulley of relatively small diameter, respective belts trained over the pulleys at the receiving and delivery ends of said frame-work, an intermediate sheet-pressing means arranged for coaction with the belt traveling around the aforesaid pulley of small diameter and effective to transversely bow a sheet jointly supported by the aforesaid belts. 15

20 4. An automatic catcher and piling mechanism comprising a vertically adjustable frame-work, a shaft at the receiving end thereof carrying a plurality of pulleys of substantially equal diameters, a second shaft at the delivery end of the frame-work carrying outer pulleys of relatively large diameters and an inner pulley of relatively small diameter, respective belts trained over the pulleys at the receiving and delivery ends of said frame-work, an intermediate sheet-pressing means arranged for coaction with the belt traveling around the aforesaid pulley of small diameter and effective to transversely bow a sheet jointly supported by the aforesaid belts. 25

30 5. An automatic catcher and piling mechanism comprising a vertically adjustable frame-work, a shaft at the receiving end thereof carrying a plurality of pulleys of substantially equal diameters, a second shaft at the delivery end of the frame-work carrying outer pulleys of relatively large diameters and an inner pulley of relatively small diameter, respective belts trained over the pulleys at the receiving and delivery ends of said frame-work, an intermediate sheet-pressing means arranged for coaction with the belt traveling around the aforesaid pulley of small diameter and effective to transversely bow a sheet jointly supported by the aforesaid belts, a sheet-receiving platform, 35

a means operatively connected with one of the aforesaid pulleys for imparting a vertical movement to said frame-work so as to control the vertical distance through which the sheets drop as they are accumulated at said platform. 40

45 6. An automatic catcher and piling mechanism comprising a mobile support, a frame-work vertically adjustable thereon, spaced shafts carried at the receiving and delivery ends of the said frame-work, the shaft at the receiving end of said frame-work carrying at least three pulleys of substantially equal diameters, the shaft at the delivery end of the frame-work carrying two outer pulleys of relatively large diameters and an intermediate pulley of relatively small diameter, respective belts trained over said pulleys, a pressure belt supported on two pressure pulleys, one of which is aligned to coact with the aforesaid pulley of small diameter, the other pressure pulley being so supported that its periphery is substantially tangent to the belt trained around said pulley of small diameter, the arrangement being such that a sheet carried toward the delivery end of the frame-work by said first three belts is progressively bowed downwardly by the pressure belt as it approaches the delivery end of the mechanism. 50
